TYPE-SETTING MACHINE

Frank H. Poeppelmeier, Dayton, Ohio, assignor,
by mesne assignments, to Set-O-Type Manufacturing Company, Cleveland, Ohio, a corporation of Delaware

Application October 20, 1931, Serial No. 569,882

38 Claims. (Cl. 276—20)

This invention relates to new and useful improvements in type-setting machines.

It is the principal object of my invention to provide a simple, economical and efficient type-setting machine that uses cold, movable type and is controlled by a typewriter keyboard.

It is another object of my invention to provide a typesetting machine of this type which lowers production costs to the minimum and eliminates all electrical solenoids.

Still another object of my invention is to provide a machine of this kind which is constructed to receive any two of a large number of magazines containing different style type faces. It is thus possible to substitute one pair of magazines for another in a few moments to obtain the style of type desired.

Other important and incidental objects of my invention will be brought out in the following specification and particularly set forth in the subjoined claims.

In the accompanying drawings illustrating my invention, Figure 1 is a perspective view of my complete type-setting machine. Figure 2 is a vertical sectional view taken through the machine, showing the mechanism in detail. Figure 3 is a sectional view taken on the line 3—3 of Figure 2, showing the arrangement of the keyboard, ejector, indexing mechanism and marginal gage. Figure 4 is a front elevational view of the magazines in place within the magazine supporting frame. Figure 5 is a vertical sectional view taken through parts of the assembled machine. Figure 6 is a detailed view showing the type shifting means. Figure 7 is an end view of the hammer shifting mechanism. Figure 8 is a top view of the upper and lower cones and some of the hammer bars. Figure 9 is a cross sectional view taken through the index casting, showing the insertible members for supporting a flat chase in place of a chase segment below the indexing means. Figure 10 is a front view of the twisted throat member between the composition board and the type ejector. Figure 11 is a perspective view of one of the component parts of the twisted throat member. Figure 12 is a perspective view of the other component part of said throat member. Figure 13 is a perspective view of a lower corner portion of the upper magazine. Figure 14 is a perspective view of a lower corner portion of the lower magazine. Figure 15 is a front view of the lower portion of the keyboard. Figure 16 is a cross sectional view taken on the line 16—16 of Figure 5, showing how the magazines are supported on the stepped bosses on the magazine

side frames. And Figure 17 is an enlarged sectional view taken through the upper and lower combs, showing the front type of a column in a position to be forced into the composing board by a hammer.

Referring to the accompanying drawings illustrating my invention, the numeral 1 designates the machine frame, which consists of four legs 2 of channel section connected at their lower ends by horizontal bracing members 3.

Secured diagonally between one front and one rear leg, a short distance above the brace members 3, is a chase index casting 4. Formed on the middle front face of the latter is an ejector bracket 5, while directly behind it a vertical drum shaft support 6 is secured to a rear leg and a respective bracing member 3. (See Figure 2.)

At one side of the lower portion of the bracket 5 a hollow boss 7 is formed on the index casting 4 to receive the front end of a drum shaft 8. The rear end of this shaft is received by a supporting bushing 9 secured to the vertical support 6.

Mounted on the shaft 8, which is adapted to be turned by a handle 10, are two drum discs 11, 11 with V notches 11^a in their upper portions. Upon these discs, which are weighted at their lower ends, a drum or segment chase 12 similar to the drum chase disclosed in my United States Letters Patent No. 1,672,953 granted July 12, 1928, is mounted in a manner described in that patent. Flat chase railways 13 are formed on the index casting 4 to receive a rail 14 which is formed in its middle portion with a hole to receive the reduced end of a rod 15. This rod, the other reduced end of which is supported by the upper end of the vertical member 6, is disposed within the V notches 11^a in the discs 11, 11 to co-operate with the rail 14 in supporting a flat chase 16 if desired, when the chase segment 12 is removed. (See Figure 9.)

The chase segment 12, as the flat chase 16 when substituted for the latter, is indexed by the hand-operated mechanism shown and described in my United States Letters Patent No. 1,753,428, granted April 8th, 1930. Briefly this mechanism comprises a bracket 17 secured to the index casting 4 to pivotally support a hand lever 18. To the lower end of the latter there is pivotally secured one end of a link 19 whose inner end is pivotally attached to an arm 20 on a shaft 21 that passes through a hole in the index casting 4. (See Figure 3.) To the end of the shaft on the opposite side of the index casting an arm 22 is secured. Attached to the latter arm is a cam bar 23 formed with a longitudinal slot through which

60

65

70

75

80

85

90

95

100

105

110

a stud 24 in a boss 25 on the index casting 4, projects. This cam bar 23 actuates an index pawl 26 through the means, and in the manner, disclosed in my said Letters Patent No. 1,753,428, 5 for the purpose of indexing the flat or segment chase below it when the handle 18 is rocked.

Secured to the top of the vertical support 6 is a hinged bracket 27 receiving through its upper face an adjustable gage member 28 which projects 10 over the chase segment 12 to control the margin of the composition set up thereon.

For the purpose of ejecting type laterally into the chase segment 12 or flat chase 16, there is mounted upon the bracket 5 an ejector 29 of the 15 type illustrated and described in my United States Letters Patents No. 1,607,170 granted November 16th, 1926, and No. 1,675,050, granted June 26th, 1928.

This ejector is driven from a suitable electric 20 motor 30 secured to a bracket 31 which is attached to the index casting 4. (See Figure 3.) To the armature shaft 32 of this motor there is secured a pulley 33 that receives a driving belt 34 which passes around a pulley 35 on the type ejector 29 to operate the latter.

Type is delivered to the ejector 29 by a composing board 36 of the type illustrated and described in my United States Letters Patent No. 1,686,031, granted October 2nd, 1928. Secured 30 to the upper portion of the ejector casing 29 is a twisted throat member 37 whose upper end is turned at an angle to receive the apex end 38 of the composing board. As shown in Figures 10 and 11, this throat member comprises two casting sections 39 and 40, which, when connected together, form a lower block portion 41 and an upper block portion 42 turned at an acute angle to each other. (See Figures 10, 11 and 12.) The casting section 39 has an axial recessed portion 43 through which passes a type tube 44 that is twisted to turn the type passing through it at an angle of substantially 126° before that type is delivered to the ejector 29. The type from the composing board 36 enters the twisted tube 44 through a rectangular hole 45 in the top of the casting section 39. The companion casting section 40 is formed with an axial recess 46 to receive the projecting portion of this twisted tube 44 when the two sections are secured together by the following means to form a correction unit between the type composing board 36 and the type ejector 29.

The lower block portions 41 of the throat member 37 are formed with screw and dowel holes to receive screws 47 and dowels 48 which not only secure the sections together, but firmly attach the unit to a flange 49 on the ejector casing 29. (See Figures 2 and 10.)

Attached by screws 50 to the sides of the upper block portions 42 of the throat member 37 are side plates 51, 51 that are formed with upper side ears 52, 52 containing holes to receive a shaft 53 upon which a spring clip 54 is mounted. The side plates 51, 51 project a short distance above the casting sections 39 and 40 to co-operate with top side flanges 55 on the latter to form a socket to receive, and hold in a correct position, the apex end 38 of the type composing board 36, with the spring clip 54 in position to press a piece of transparent material 56 against the open vertical type channel 57 in the lower end of said board. (See Figure 10.) The clip 54 permits the easy removal of the transparent piece 56 to clean the type channel 57 which it covers.

The type composing board 36 is the same as that illustrated and described in my said Letters

Patent No. 1,686,031, except that the twisted vertical type tubes 58 and the inclined side channels with which their lower ends communicate, are on one side only of the triangular core board 59, and that is the side toward the typewriter keyboard 60, the latter being secured by brackets 61 between the front legs 2, 2 of the machine frame.

The tube receiving head portion 62 of the type composing board 36 is formed with side holes 63 that register with holes in the sides 64 of a rectangular magazine frame 65 secured to the top portions of the legs 2.

Pivot pins 66 are inserted in these registering holes to firmly secure the top of the composing board to this magazine frame.

The magazine frame 65, is secured to the rear legs 2, 2 of the main frame immediately above a horizontal tie bar 67 attached to them. Just below this tie bar the main frame is braced by inclined members 68, 68 connected to said legs.

The side members 64, 64 of the magazine frame 65 terminate at their front ends in down-turned portions 69 which are secured to the front legs 2, 2. Secured between the lower ends of these down-turned portions 69, 69 of the magazine frame side members 64 is a spring plate 70. Above this plate, a hammer supporting casting 71 is secured between the members 64, 64. This casting has a flat front surface, and a recessed inner portion 72 with bosses 73 at the ends of the latter. Formed in these bosses are holes to receive the pivot pins 74 that are secured in the ends of a hammer shift bar 75. (See Figures 2, 5, 6 and 7.)

The hammer shift bar 75, which is employed to place the type hammers in position to eject type belonging to the upper or lower case, comprises a single casting formed with oppositely disposed grooves in its ends to receive two hammer shafts 76 and 77. The top face portion of the hammer shift bar 75 is formed with two parallel rows of hammer slots 78 and 79. These slots 78, which are shorter than the slots 79, are in horizontal alignment with them. (See Figure 7.) The bottom portion of the hammer supporting casting 71 is formed with similar slots.

Pivotedly secured to the upper hammer shaft 76, one in each slot 79, is a plurality of upper type delivery hammers 80; and to the lower hammer shaft 77 there is pivotedly secured a series of lower delivery hammers 81, one in each slot 79. The upper hammers 80 are preferably T shaped stampings, while each lower hammer 81 is an elongated rectangular stamping with a raised portion containing a long slot 82 on one side of its middle portion, and an enlarged part on the other side of the latter, containing a short slot 83. Each pair of upper and lower hammers 80 and 81 is slidingly connected by studs 84 on the stem portions of the upper hammers, that project into the long slots 82 of the lower hammers. (See Figure 5.)

Each lower hammer 81 is slidingly secured to the upper end of the substantially right angled foot portion 85 of a hammer operating lever 86 by a stud 87 on the latter that is received by the short slot 83 in the former. These operating levers 86 are free to rock in slots in a boss 88 formed lengthwise of the hammer supporting casting 71 at its lower end. A longitudinal groove 89 formed in this end of the casting receives a hammer operating lever shaft 90 to which the lower ends of the hammer operating levers 86 are pivotally connected. (See Figures 2 and 5.) Slightly beyond the portion thereof which receives the shaft 90, each operating lever has a recessed end 91 to

80

- receive one end of a coil return spring 92, the other end of which is secured to the spring plate 70. (See Figures 2 and 5.)
- The levers 86, and through them the type hammers, are operated by the keys 93 of the typewriter keyboard 60 through the agency of the following connecting means. The heel end 94 of each operating lever 86 is formed with a hole to receive an end of a coil spring 95. To the lower hook end of each spring 95 there is connected one end of a line 96 such as armature wire, the lower end of which is secured to an apertured ear 97 on the particular key 93 that is to actuate this lever. (See Figure 5.)
- These typewriter character keys 93 are pivotally secured at their rear ends to key shafts 98 secured to a shaft support 99 within the key case 100.
- The hammer shift bar 75 is operated by the following means through either one of the shift keys 101 or 102, each one of which is pivotally secured at its rear end to a key shaft 98. At its middle portion each shift key is formed with an apertured ear 103 to which one end of a line 104 such as armature wire is secured. The other end of this wire is secured to a turnbuckle 105. To the upper end of the latter there is secured a similar wire 106 that is connected at its upper end to the apertured end 107 of a bell crank 30 shift bar lever 108.
- Each shift bar lever 108 has formed in its central portion a hole which receives the outer end of a respective pivot pin 74 that is fitted in the outer end of the hole in one of the bosses 73 35 on the hammer supporting casting 71.
- This shift bar lever 108 is formed with two opposite shoulder projections 110 and 111 for engagement with the hammer shafts 76 and 77 respectively, so that when the shift bar lever is turned by a shift key, it will rotate the hammer shift bar 75 to a position wherein the hammers carried by it will deliver either upper case or lower case type from the magazines to be hereinafter described. A coil return spring 112 is 40 connected between the shouldered end 110 of the shift bar lever 108 and a spring plate 113 formed on one of the magazine side frame members 64. For the purpose of returning the hammer shift bar 75 to its normal position a coil spring 114 is 45 secured between its upper portion and the spring plate 113. (See Figure 6.)
- The type which the hammers 80 and 81 deliver to the type composing board 36 are contained in a pair of magazines 115 and 116. The upper magazine 115 is adapted to contain the lower case type, while the lower magazine 116 is adapted to receive the upper case type. Each magazine consists of side frame members 117, 117 to which are secured at right angles bottom reinforcement plates 118. To these plates suitable vanes 119 are staked to provide between them the type receiving grooves. (See Figures 4 and 16.) For the purpose of conveniently carrying each magazine, a handle 120 is attached to the middle part 60 of each of its side frame members 117. While I have illustrated type magazines of the form just described, any other suitable magazines of the same general type may be employed if desired.
- Secured to the front reinforcing plate 118 of the upper magazine 115 is a comb 121. This comb is preferably an L shaped brass casting provided with vertical slots between upright ribs 122 formed on its front portion. Slots 122^a in 70 the bottom of the casting extend inwardly from the spaces between these ribs to give the lower hammers free play. (See Figure 13.)
- Each rib projects a slight distance above, and engages the middle front portion of a type vane 119. The upper portion of each rib is formed to receive a straddle insert 123 that projects to the top of the rib, so that the ribs and flanged portions of the inserts will form at the front ends of the grooves between the vanes, nests to receive the type from the grooves. To the front face of the comb casting 119 there is secured a cover plate 124 formed with slots which register with the slots in the comb, a broken away portion of that plate being shown in Figure 13.
- The upper side faces of the ribs 122 are tapered to guide the front type of the column in the groove to the inserts 123 at the end of the groove, where that type is held against them by gravity until forced through the opening below by a respective hammer 80 when the key 93 corresponding to the latter is pressed by the operator.
- The inserts 123 are formed on their rear faces with small beveled projections 123^a to assist gravity in holding the front type in the opening in the front part of the comb until pressed through it by one of the hammers.
- A comb 125 is secured to the front portion of the reinforcing plate 118 of the lower magazine 116. This comb is also an L shaped brass casting formed at its front portion with vertical ribs 126. In their top portions these ribs are formed with grooves, to receive straddle inserts 127, which divide the space between the ribs into front and rear compartments. The legs of these inserts terminate at their lower ends in offset heels to engage the companion heels on the legs of the adjacent inserts to close up the space between them. (See Figure 14.) A cover plate 128 is secured to the front face of the comb 125. This plate, a broken away portion of which is shown in Figure 14, is formed with slots to permit the hammers 81 a free entrance into the spaces between the ribs.
- The spaces between the ribs 126, the front faces of the inserts 127 and the cover plate 128, form openings through which the type ejected from the upper comb 121 may drop into the composing board, since the tops of the twisted tubes 58 in the latter are directly below these openings when the magazines 115 and 116 are mounted in the magazine supporting frame. (See Figure 5.)
- For the purpose of properly supporting the upper and lower magazines 115 and 116 in the machine, the magazine side frame members 64, 64 have formed on their inner front portions stepped bosses 129 and 130. (See Figure 17.)
- The upper magazine 115 rests at its front corner portions upon the steps 129, while the lower magazine 116 rests at its front corner portions upon the steps 130. Gage pins 131 secured in holes in the boss portions 129 on the side frame members 64 engage the sides of the upper magazine to align its comb discharge openings with the front openings in the comb on the lower magazine, which is in turn aligned by gage pins 132 in said magazine side frame members to bring the type discharge openings in the lower comb 125 directly over the type tubes 58 in the composing board. (See Figures 5 and 16.) At its rear end the lower magazine 116 rests upon a boss 133 formed on a rest member 134 secured between the magazine side frame members 64. Projecting upwardly from the rear upper face portion of this lower magazine is a stud 135 upon which the rear part of the upper magazine 115 rests. (See Figure 2.)

When the magazines 115 and 116 are mounted in the machine as above described, the hammers 80 and 81 are free to be projected into the slots in the combs carried by these magazines to eject type from them into the composing board. Since these hammers are pivoted to the shift bar 75, the upper hammers 80 may be moved by it into the slots in the upper comb 121 to eject lower case type therefrom while the lower hammers 81 are simultaneously withdrawn from the lower magazine comb 125.

Conversely, when either one of the shift keys 101 or 102 is pressed down, it will rock the hammer shift bar 75 in the opposite direction to withdraw the upper hammers 80 from the slotted comb 121 on the upper magazine 115 and project the lower hammers into the slotted comb 125 on the lower magazine to discharge upper case type therefrom.

In Figure 5 the shift keys are in their up positions, permitting the spring 114 to hold the hammer shift bar 75 in a position to maintain the upper hammers 80 in type ejecting positions within the slots in the comb 121 on the front end of the upper magazine 115. With the front type of the columns in the upper magazine grooves held by gravity against the inserts 123 in front of the grooves, the depression of the keys 93 will pull the front ends of the corresponding hammers 80 down to force this loosely held front type through the openings between the ribs and the inserts in the upper comb, and on through the front openings between the ribs and the inserts in the comb 125 below, into the twisted tubes 58 with which these openings communicate in the composing board. (See Figures 2 and 17.) In Figure 17 I have shown a front type 136 in a position to be ejected by a hammer 80 from the comb 121 of the upper magazine, needing only the depression of the key connected to that hammer to cause the latter to tap that type through the comb opening below.

If it is desired to eject an upper case type from the lower magazine 116, either one of the shift keys 101 or 102 is depressed to turn the hammer shift bar 75 to a position to withdraw the hammers 80 from the upper comb and project the hammers 81 into the slots in the lower one. Then when the key 93 corresponding to the upper case type desired is depressed, the hammer 81 for that key will be rocked by it to tap that type through the rear opening in the comb 125 in which it is held by gravity against the inserts 127 above small beveled projections 137 thereon. Such a type is designated by the numeral 138 in Figure 17, where it is shown in a position against an insert 127 within the opening between the latter, the ribs and the front portions of the vanes. Pressure of the columns of type behind it is always sufficient to hold the front type within that opening against the inserts until engaged by the hammer. When struck by the latter, the type will be dislodged from its weak support and fall through the opening directly into the type tube in the composing board. (See Figure 5.)

For the purpose of holding the hammer shift bar 75 in a position to maintain the hammers 81 in a position to deliver type from the lower magazine 116, I have provided in the front portion of the key case 100 an L slot 139 to hold the shift key 102 down until it is desired to set the hammer shift bar for the delivery of lower case type from the upper magazine.

A slot 140 having a central offset portion 141 is formed in the right side of the front face of the

key case 100 to hold the shift key 101 at a half way point to maintain the hammers 80 and 81 in a neutral position while the magazines are being removed from, or mounted on, the machine.

A curved hammer cover plate 142 is pivotally secured at its lower side portions by pins 143, 143 between the magazine side frame members 64, 64 so that it may be easily moved to uncover or cover the type ejecting hammers.

The two middle grooves in each magazine are adapted to contain quads for spacing purposes. The reason two grooves are set aside for this purpose is that there are more quads needed than type of any one character.

These quads are ejected by the hammers 80 and 81 in the same manner as the type are forced out of the combs, except that the space bar 144, instead of the keys, is employed for the purpose of actuating these hammers. The two wires 96, 96 that are connected to the two sets of hammers 80 and 81 which eject the quads from these middle grooves in the magazines, are connected at their lower ends to two levers 145 and 146 respectively, which are pivotally secured at their inner ends to shafts 98 within the key case 100. The front ends of these levers project almost to the vertical plane of the space bar 144, but are just below the normal horizontal plane in which said bar lies when in its normal position.

In order that the space bar 144 may be adapted to actuate either one of these quad ejecting levers, I have secured to the under surface of the bar a longitudinally shiftable trigger 147 formed with a side projection 148 which is adapted to be moved to a position over either one of the free ends of the levers 145 and 146. When this trigger, for instance, is shifted by the finger grip 149 on its front portion, to a position wherein its projection 148 is over the free end of the lever 145, the space bar 144 may be depressed to eject the quads in the magazine grooves corresponding to that lever until they are exhausted. Then, by shifting the trigger 147 in the opposite direction to bring its projection 148 over the free end of the lever 146, the spacing quads in the pair of grooves in the magazines corresponding to this lever will be ejected at the desired times by the space bar. (See Figures 2 and 3.)

In operation, a pair of magazines containing the desired style of type in upper and lower case characters is placed upon the magazine side frame members in a position to properly deliver this type to the composing board when the type board keys are operated. If the style of type called for is pica, the pair of magazines containing it are withdrawn from storage and placed in the machine. Later, if the elite style of type is desired, the pair of magazines carrying it may be easily and quickly substituted for the pica magazines on the magazine side frame members. Any number of magazines filled with different styles of type may thus be kept on hand for use when desired.

After the pair of magazines containing the selected type are in place in the machine, the shift keys, type keys and space bar on the board 60 may be operated, causing the hammers to force the type corresponding to the actuated keys from the nests in the combs into the type composing board. If an upper case type character is desired, one of the shift keys is depressed to turn the hammer shift bar 75 to a position to introduce the hammers 81 into the slotted comb 125 of the lower magazine 116 for the purpose of ejecting that type into the com-

80

posing board. Lower case type is discharged by the hammers 80 from the comb on the upper magazine when the shift keys are in their extreme upper position.

- 5 Before the operator starts to set up a composition, she actuates an electric switch 149 secured to one of the legs 2, to start the ejector motor 30. When the type and quads are discharged from the combs of the magazine in response to the operation of the keys and space bar, they drop in quick succession into the twisted tubes of the composing board, by which they are turned 90° before entering the tubes in the twisted throat member 37. During their descent through 15 the latter, the type and spacing quads turned 126° more, so that they will be forced by the ejector 29 into the grooves of the chase 12 in a proper printing position. In other words, the type is adjusted to the proper angle of the chase 20 during its descent through the transfer chute formed by the composing board and the throat member.

After the selected type and spacing quads enter the motor-operated ejector 29, one side 25 of whose casing is removed in Figure 2, they are forced by it into a groove in the chase. When one line is completed, the chase is moved by the indexing mechanism before described to present the next groove in it to the discharge 30 opening in the ejector, this sequence of indexing and ejecting operations being continued until the complete page composition is set upon the chase. The latter, whether it be the segment 12 or the flat chase 16, is then removed for 35 insertion in a suitable press.

Having described my invention, I claim:

1. In a type-setting machine, an inclined magazine provided with a series of type grooves, a type delivery member at the lower end of said 40 magazine, a vertical transfer chute below said delivery member, the latter being provided with type discharge openings over said chute, that communicate with the type grooves in the magazine, a flat surface formed with a small beveled projection in each opening against which the front type of each column in said grooves is held in said opening by the weight of that column of type, a series of keys, and hammers 45 mechanically operated by respective keys to engage from above corresponding front type in said openings to force them through the latter into the transfer chute below.

2. In a type-setting machine, an inclined magazine provided with a series of type grooves, a type delivery member at the lower end of said magazine, a vertical transfer chute below said delivery member, the latter being provided with type discharge openings over said chute, that communicate with the type grooves in the magazine, a flat surface formed with a small beveled projection in each opening against which the front type of each column in said grooves is held in said opening by the weight of that column of type, a series of key levers, hammers 65 adapted to engage from above corresponding front type in said openings to push them through the latter into the transfer chute below, an operating lever for each hammer, and a line connection between each key lever and its corresponding hammer operating lever.

3. In a type-setting machine, an inclined magazine provided with a series of type grooves, a type discharge comb secured to the lower end of said magazine, a vertical transfer chute below said comb, vertical ribs on the comb, adapt-

ed to bear against the lower end of the magazine, each pair of ribs providing between them a space to receive the front type of a column of type in a respective magazine groove, flanges on said ribs at the rear of the type receiving spaces between them, the front type of said columns of type being held by gravity against said flanges, in the spaces between the ribs, a series of keys, and hammers operated by respective keys to engage from above corresponding front type in the spaces between the ribs to force them through said spaces into the transfer chute below.

4. In a type-setting machine, a pair of superimposed inclined magazines, one provided with grooves to receive upper case type and the other provided with grooves to receive lower case type, each magazine provided with a series of type discharge openings at the lower ends of said grooves, a vertical transfer chute below the type discharge openings in the lower magazine, a series of keys, ejecting members operated by respective keys to force selected type through said openings into the transfer chute below, a set of ejecting members for each magazine, a shift key, and means actuated by the latter for placing one set of ejecting members in position to deliver type from one magazine into the transfer chute and for simultaneously withdrawing the other set of ejecting members from a type engaging position.

5. In a type-setting machine, of pair of superimposed inclined magazines, one provided with grooves to receive upper case type and the other provided with grooves to receive lower case type, each magazine provided with a series of type discharge openings at the lower ends of said grooves, a vertical transfer chute below the type discharge openings in the lower magazine, means in each opening against which the front type of each column in said grooves is held in said opening by the weight of that column of type, a series of keys, hammers operated by respective keys to engage from above corresponding front type in said opening to force them through the latter into the transfer chute below, a set of hammers for each magazine, a shift key, and means actuated by the latter for placing one set of hammers in position to eject type from one magazine into the transfer chute, and for simultaneously withdrawing the other set of hammers from a type engaging position.

6. In a type-setting machine, a pair of superimposed inclined magazines, one provided with grooves to receive upper case type and the other provided with grooves to receive lower case type, each magazine provided with a series of type discharge openings at the lower ends of said grooves, a vertical transfer chute below the type discharge openings in the lower magazine, means in each opening against which the front type of each column of type in said grooves is held in said opening by the weight of that column of type, a series of keys, hammers operated by respective keys to engage from above corresponding front type in said openings to force them through the latter into the transfer chute below, a set of hammers for each magazine, a pivoted shift means upon which the two sets of hammers are mounted, a shift key lever, and a connection between said shift key lever and the shift means to rock the latter to place one set of hammers in position to eject type from one magazine and for simultaneously withdrawing the other set of hammers from a type engaging position.

7. In a type-setting machine, a pair of superimposed inclined magazines, one provided with grooves to receive upper case type and the other provided with grooves to receive lower case type, each magazine provided with a series of type discharge openings at the lower ends of said grooves, a vertical transfer chute below the type discharge openings in the lower magazine, means in each opening against which the front type of each column of type in said grooves is held in said opening by the weight of that column of type, a series of keys, two sets of hammers for each key, one set of hammers for the upper magazine and the other set of hammers for the lower magazine, a pivoted shift member, one set of hammers being pivotally connected at their rear ends to one free end of the shift member, and the other set of hammers being pivotally connected at their inner ends to the other free end of the shift member, the hammers of the upper set being slidingly connected at their middle portions to the hammers of the lower set, a connection between each lower hammer and its corresponding key, a shift key lever, and a connection between said shift key lever and the shift member to rock the latter to place one set of hammers in position to eject type from one magazine and for simultaneously withdrawing the other set of hammers from a type engaging position.
8. In a type-setting machine, a pair of superimposed inclined magazines, one provided with grooves to receive upper case type and the other provided with grooves to receive lower case type, each magazine provided with a series of type discharge openings at the lower ends of said grooves, a set of hammers for forcing type through the openings in the upper magazine, a second set of hammers for forcing type through the openings in the lower magazine, a pivoted shift member to one free end of which the hammers of one set are secured and to the other free end of which the hammers of the other set are secured, each lower hammer formed with an upper elongated slot and a lower elongated slot, a projection on each upper hammer, a pin on each projection entering the upper slot in the hammer below it, an operating lever for each lower hammer, pivoted at its lower end, a foot portion on the upper end of each operating lever, a stud on said foot portion entering the slot in a respective lower hammer, a series of key levers, a line connection between the lower end of the foot portion of each operating lever and a respective key lever, coil return springs secured to said operating levers to return them to a normal position after they have been depressed by said key levers, a shift key lever, and a connection between the latter and the shift bar for the purpose specified.
9. In a type-setting machine, a pair of superimposed inclined magazines, one provided with grooves to receive upper case type and the other provided with grooves to receive lower case type, a type discharge comb secured to the front end of each magazine, the upper comb formed with a type discharge opening at the front end of each groove, the lower comb formed with two rows of spaced openings, each opening in the upper row adapted to receive type from each groove in the lower magazine, the openings in the front row of the lower comb being directly below the type discharge openings in the upper comb, a type chute below the openings in the lower comb, and ejecting means for forcing type from the upper comb through the front openings in the lower comb into the type chute, and type from the lower comb directly into said chute.
10. In a type-setting machine, a pair of superimposed inclined magazines, one provided with grooves to receive upper case type and the other provided with grooves to receive lower case type, a type discharge comb secured to the front end of each magazine, each comb provided with hammer receiving slots in its front face, opposite the front ends of the magazine grooves, type retaining members at the front ends of the slots in the upper comb, partition type retaining members in the middle portions of the slots in the lower comb, the spaces in front of said partition members being directly under the type receiving spaces in the upper comb, a type chute below the lower comb, hammer shifting means, a set of type hammers carried by the shifting means for entrance into the slots of the upper comb to force type therefrom through the slots in front of the partition members in the lower comb into the transfer chute, and a second set of hammers carried by said shifting means for entrance into the slots in the lower comb to force type from their positions against the rear faces of said partition members directly into the type chute.
11. In a type-setting machine, a pair of superimposed inclined magazines, one provided with grooves to receive upper case type and the other provided with grooves to receive lower case type, a type discharge comb secured to the front end of each magazine, vertical ribs on the front face of each comb, the ribs on the lower comb being wider than those on the upper comb, the space between the ribs being opposite the magazine grooves, straddle type-retaining inserts secured to the rear upper portions of the ribs in the upper comb, a slotted cover plate attached to the upper comb in front of said inserts, straddle type-retaining inserts secured to the middle top portions of the ribs on the lower comb, a slotted cover plate attached to the front face of the lower comb, the type receiving slots in the upper comb registering with the spaces between the inserts and the cover plate in the lower comb, a type chute below the latter, hammer shifting means, a set of type hammers carried by the shifting means for entrance into the slots of the upper comb to force type therefrom through the front slots in the lower comb, into the transfer chute, and a second set of hammers carried by said shifting means for entrance into the slots in the lower comb to force type from their positions against the rear faces of the partition inserts directly into the type chute.
12. In a type-setting machine, a supporting frame, a pair of superimposed magazines mounted on the top portion of said frame, one provided with grooves to receive upper case type and the other provided with grooves to receive lower case type, a shift bar pivotally secured in said frame, in front of said magazines, the upper face of said shift bar formed with two parallel rows of hammer slots, said bar provided with oppositely disposed grooves in its ends, a hammer shaft secured in each groove, a set of hammers pivotally secured at their rear ends to one hammer shaft, a hammer for each slot in one row, to eject type from one magazine when their free ends are moved downwardly, and a second set of hammers, one for each slot in the other row, to eject type from the other magazine when their free ends are moved downwardly, and means for rocking the hammer shift bar to project one set of hammers

- into a type ejecting position with respect to their magazine, and simultaneously to withdraw the other set of hammers from a type ejecting position with respect to the other magazine.
13. A type magazine comprising a pair of side members, bottom reinforcing plates secured between said side members, vanes secured to the top portions of said plates to provide type receiving grooves between them, and a type discharge comb secured to the front reinforcing plate, and having type-discharge openings therein at the front ends of the grooves between the vanes to receive type therefrom. 80
14. A type-setting machine comprising a supporting frame, a magazine receiving structure at the top portion of said frame, a pair of type containing magazines removably mounted, one above the other, and in an inclined manner, upon said structure, a keyboard mounted in the lower portion of said supporting frame, a type chase also mounted in the latter, a transfer chute secured in said frame between the lower magazine and the type chase, a hammer shift device pivotally mounted in said frame below the front ends of said magazines, a set of type-ejecting hammers for each magazine, carried by the hammer shift device, type keys and shift keys in said keyboard, connections between the shift keys and the hammer shift device to project one set of hammers into a type ejecting position with respect to its magazine and to withdraw the other set of hammers from a type ejecting position with respect to its magazine, and connections between the type keys and the hammers to operate the latter when the keys are depressed. 90
15. In a type-setting machine, a magazine provided with type receiving grooves and two grooves to receive spacing quads, a pair of members for ejecting said quads, one member for each quad groove, a pair of levers, one lever connected with each ejecting member to actuate the latter, a space bar in front of said levers, and shiftable means on said space bar for engagement with one or the other of said levers to actuate a selected quad ejecting member when the space bar is depressed. 100
16. A type turning member for type-setting machines, comprising a throat block divided in two sections, one section formed with a recessed portion in its inner face, the other section having a recessed portion in its inner face, a twisted type tube projecting downwardly through the recessed portion of the last named section, and fitting into the recessed portion of the first section when said sections are united, and means for connecting said sections together. 110
17. In a type-setting machine, a supporting frame comprising four connected legs, a keyboard supported between the two front legs, a type chase and ejector assembly supported diagonally between a front leg and two rear legs of said frame, a type containing magazine supported in an inclined manner upon the top of said frame, a composing board immediately below the front end of said magazine, key-operated means for ejecting type from said magazine into the composing board, and a type turning throat block between the lower end of the composing board and the ejector assembly. 120
18. In a type-setting machine, a supporting frame, a type composing board secured vertically within the front portion of said frame, and formed with type-receiving openings in its top, a pair of superimposed type containing magazines, a type delivery member having two rows of par-
- titioned openings, secured to the front end of the lower magazine, a type delivery member secured to the front end of the upper magazine, the second type delivery member having type discharge openings, and means for securing said magazines on the supporting frame with the type discharge openings in the upper delivery member over the front row of partitioned openings in the lower type delivery member, and with the latter member directly over the type receiving openings in the composing board. 130
19. In a type-setting machine, a supporting frame, a pair of portable superimposed magazines mounted on the top portion of said frame, one provided with grooves to receive upper case type and the other provided with grooves to receive lower case type, a pivoted shift means in front of said magazines, a set of hammers carried by said shift means for the ejection of type from the upper magazine and a pair of hammers carried by said shift means for the ejection of type from the lower magazine, means for turning said shift means to project one set of hammers into a type ejecting position with respect to its magazine and for simultaneously withdrawing the other set of hammers from a type engaging position with respect to its magazine, and means for placing said shift means in a neutral position to permit the removal of the magazine. 140
20. In a type-setting machine, a supporting frame, a pair of portable superimposed magazines mounted on the top portion of said frame, one provided with grooves to receive upper case type and the other provided with grooves to receive lower case type, a pivoted shift means in front of said magazines, a set of hammers carried by said shift means for the ejection of type from the upper magazine and a pair of hammers carried by said shift means for the ejection of type from the lower magazine, a keyboard case, a shift key lever in the latter, a connection between said shift key lever and the hammer shift means to turn the latter when the shift key lever is depressed, said keyboard case formed with a vertical slot to receive said key lever, said vertical slot having a horizontal offset at its middle portion to receive said shift key lever to hold the shift means and the hammers carried thereby in a neutral position to permit the removal of the magazines. 150
21. A chase holder for type-setting machines, comprising a support, a shaft secured to said support, a pair of discs formed with V-shaped notches, on said shaft, to support a chase segment, and a rod adapted to be inserted in said frame, over the notches in said discs, to support a flat chase when the chase segment has been removed. 160
22. In a type-setting machine, the combination of a plurality of type cases, ejecting members adapted to engage the endmost type therein, operating connections between the keyboard and ejecting members, and shift mechanism acting on the ejecting members to advance one and withdraw the other according to which case is to be active. 170
23. In a type-setting machine, the combination of two type channels for individual type, two ejecting devices therefor, a keyboard, mechanism controlled thereby for operating the two ejecting devices as a unit, and shift mechanism acting on the ejecting devices for rendering one or the other ejecting device ineffective. 180
24. In a type-setting machine, the combination of two type cases, each having channels 190

- for individual type, two sets of ejecting devices for operating on the type in the channels of the respective cases, mechanism for operating two ejecting devices of different sets simultaneously, 5 and shift mechanism adapted to move the ejecting device for rendering one or the other ejecting device ineffective.
25. In a type-setting machine, the combination of two channeled type cases, and each having channels side by side, two sets of ejecting hammers adapted to act on type in the corresponding channel and eject the same therefrom, and mechanism operated by the keyboard for moving the two hammers corresponding to a 10 key when the key is operated.
26. In a type-setting machine, the combination of two channeled type cases, located one above the other in inclined position and each having channels side by side, two sets of ejecting hammers adapted to move downwardly onto the end-most type in the corresponding channel and eject the same, a chute down which the type may travel when ejected, a keyboard, mechanism operated thereby for moving the two hammers corresponding to a key when the key is 15 operated, and shift mechanism for rendering one or the other set of hammers idle.
27. The combination of two type cases, a common chute, individual passageways from respective type cases joining and discharging into said chute, a passageway from the more distant case, moving past the end of the nearer case, and means adapted to extend through the latter passageway for ejecting the type from the nearer case.
- 35 28. In a type-setting machine, the combination of two type cases, two sets of ejecting hammers operating on the respective cases, two bars carrying the respective sets of hammers, said bars being connected and parallel to make a frame intermediate pivoted on an axis parallel with the bars, and means for rocking the frame on its axis to cause either set of hammers to be active.
- 40 29. The combination of two type cases, two ejection devices therefor, connected together, means for operating the ejection devices as a unit, and means acting on the ejection devices for rendering either of said devices ineffective and the other effective.
- 50 30. The combination of two type cases, each composed of a number of channels, two sets of ejecting hammers, the corresponding hammers of the two sets being linked together, and connections between the keys and the individual hammers of one set, whereby said keys may simultaneously operate both hammers, and means for rendering either set of keys idle, notwithstanding its operation.
- 60 31. In a type-setting machine, the combination of an inclined type case having channels down which type may slide by gravity, a series of individual hammers for positively shoving the end-most type from the corresponding channel, a keyboard having key levers, and mechanical connections between the key levers and the hammers.
32. In a type-setting machine, the combination of an inclined type case having channels down which type may slide by gravity to the lower end of the type case, ejecting mechanism for knocking the endmost type out of the line and into a chute down which it may descend by gravity, a keyboard having key levers, and wires and springs connecting the key levers with the ejecting hammers. 80
33. The combination of a gravitational type case, means for frictionally supporting the endmost type, a set of hammers, a set of key levers, mechanical connections between the key levers and the respective hammers, means for causing the corresponding hammer to act downwardly on the endmost type and knock it free from the line thereof so that such type may pass downwardly by gravity into the chute. 85
34. In a type-setting machine, the combination of a case having a plurality of channels, a manual operating member, means actuatable thereby for ejecting type from either of said channels, and a shifting device mounted on the operating member for determining which channel shall be active, said device being readily movable by the operator's hand while on said operating member. 90
35. In a type-setting machine, the combination of a case having a plurality of channels for holding space type, a keyboard having a space bar, means for ejecting spaces from either of said type channels by the operation of the space bar, and a shifting device mounted on a space bar for determining which channel shall be active. 95
36. In a type case, the combination of an upright frame, a type case at the top thereof, a keyboard at the front thereof, a type receiving segment located at an oblique angle within the lower portion of the frame, mechanism operated by the keys for discharging type from the case, and means for conducting the discharged type to the segment and twisting it during the discharge sufficiently to present it at an oblique angle to the end of the segment, and means for shoving such type onto the segment. 100
37. In a type-setting machine, the combination of a plurality of type cases, mechanism for ejecting type therefrom, a shift key adapted to render the ejecting mechanism active for either type case, and means for holding the shift key in an intermediate neutral position with the ejecting mechanism in a neutral position to permit the removal of the type cases. 105
38. In a type-setting machine, the combination of two type cases, two sets of ejecting hammers for coacting with the respective cases, mechanism for operating both of said hammers as a unit, a shifting device for withdrawing one set of hammers and rendering the other set active to select a case according to the position of the shifting device, and means for retaining the shifting device in an intermediate neutral position to hold both sets of hammers withdrawn. 110

FRANK H. POEPPELMEIER.

DISCLAIMER

1,975,799.—*Frank H. Poepelmeier*, Dayton, Ohio. TYPE-SETTING MACHINE.
Patent dated October 9, 1934. Disclaimer filed October 10, 1934, by
the assignee, *Set-O-Type Manufacturing Company*.

Hereby enters this disclaimer to those claims which are in the following words, to wit:

“15. In a type-setting machine, a magazine provided with type receiving grooves and two grooves to receive spacing quads, a pair of members for ejecting said quads, one member for each quad groove, a pair of levers, one lever connected with each ejecting member to actuate the latter, a space bar in front of said levers, and shiftable means on said space bar for engagement with one or the other of said levers to actuate a selected quad ejecting member when the space bar is depressed.”

“34. In a type-setting machine, the combination of a case having a plurality of channels, a manual operating member, means actuatable thereby for ejecting type from either of said channels, and a shifting device mounted on the operating member for determining which channel shall be active, said device being readily movable by the operator's hand while on said operating member.

“35. In a type-setting machine, the combination of a case having a plurality of channels for holding space type, a keyboard having a space bar, means for ejecting spaces from either of said type channels by the operation of the space bar, and a shifting device mounted on a space bar for determining which channel shall be active.”

[Official Gazette October 30, 1934.]
